UNITED STATES PATENT OFFICE.

EDWARD R. PILLARS AND HENRY C. LEESEBERG, OF FOSTORIA, OHIO.

SELF-LOCKING BASE-FUSE.

1,383,751.

Specification of Letters Patent.

Patented July 5, 1921.

Application filed January 12, 1918. Serial No. 211,655.

To all whom it may concern:

Be it known that we, EDWARD R. PILLARS and HENRY C. LEESEBERG, citizens of the United States, residing at Fostoria, in the 5 county of Seneca and State of Ohio, have invented certain new and useful Improvements in Self-Locking Base-Fuses; and we do hereby declare the following to be a full, clear, and exact description of the same, reference being had to the accompanying drawings, forming part of this specification.

The object of this invention is to provide a fuse that will give absolute protection in use and will consist of less parts than any 15 fuse now available. Another object of the invention is to provide a fuse that can only be fired while the shell to which it is attached is rapidly rotating, this object being accomplished by having a safety guard 20 slideable in a track or groove, and having a hole which is out of alinement with the central hole in the primer at all times except when thrown into alinement by centrifugal action of the shell. A further object of the invention is to provide a primer cup and guard that can be assembled as a unit, and one which becomes permanent when assembled.

In the drawings,—

Figure 1 is a vertical section through our 30 device.

Fig. 2 is a view at right angles to Fig. 1.

Fig. 3 is a section on line 3—3 of Fig. 1.

Fig. 4 is a view showing the fuse ready to arm.

The body 1 of the fuse is of the usual type, threaded left-handed as at 2 for the major part of its length, the threads ending in a reduced portion 3, just above the base 4, the latter being of a considerably greater 40 diameter than the smooth portion 3, so as to considerably overlie the threaded hole in the shell. Holes 5 are provided to receive the lugs of a spanner wrench, the base 4 being level with the base of the shell when the 45 fuse is screwed in, the base flange fitting in a counter-sunk recess in the base, as is usual.

The cylindrical plunger 6 slides in the usual plunger cavity 7 in the base, and carries a firing pin 8 having a hardened tapered 50 point 9. An intermediate portion 10 between the firing pin and the plunger coaxial and integral with these parts is provided on its upper face 11 with grooves or indentations 12 for a purpose hereinafter 55 described.

The primer holder 13 is provided with a central chamber 14 for the reception of the usual mercury fulminate, and an orifice 15 establishing communication between the fulminate chamber and the shell chamber (not 60 shown) containing the main charge. Centrally of the primer holder is a flange 16 which is supported by shoulder 17 of the body in such position that the lower face of the primer is just above the point of the firing pin when the plunger is resting on the 65 bottom of the cavity.

Slidably mounted in the groove 18 of the primer is a guard member 19 composed of a block 20 integral with a slide 21, centrally 70 perforated as at 22, to permit the firing pin to pass through to detonate the fulminate when the guard is thrown to its extreme position by centrifugal force sufficient to overcome the pressure of a spring 23 loosely received in a recess 24 in the block. The lower surface 25 of the block is roughened in any way, as for instance by grooves or indentations 26, which coöperate with the 75 grooves 12 to prevent accidental displacement of the guard member.

In order to assemble the parts of the fuse, the primer chamber is filled with the charge of fulminate and the guard member placed in the groove, and the whole inserted in the 80 body as a unit. A boosting charge 27 may be used, if desired, or the primer may directly ignite the main charge of powder through the orifice 15. In either event, the primer holder and guard are made a permanent 85 unit when the upper rim of the body is spun over the flange of the primer holder as shown at 28 in Fig. 1.

Under ordinary circumstances the firing pin is prevented from touching the fulminate 90 in two ways, one, by the block 20 acting as a stop for the shoulder between the pin and the part 10, and the other by the hole 22 being out of alinement with the path of the point of the firing pin, due to the action of the 95 spring 23 forcing the guard along the slot or groove to a point where the outer edge of the slide 21 will engage the wall of the body. The roughness of the parts 12 and 26 serves to prevent displacement of the guard against 100 the action of the spring, but such displacement is caused by any centrifugal action in the projectile, such as is given to a shell on its being fired from a rifled gun. When fired, 105 the plunger 6 and firing pin 8 are held tightly 110

against the bottom of the cavity 7, disengaging the roughened surface 25 of the guard from the similarly roughened surface 11 of the portion 10 so that the centrifugal force, 5 which acts in opposition to the spring 23, throws the heavier part of the guard, *i. e.*, the block, against the side wall of the body and thereby withdraws the block from the path of the intermediate portion 10 of the 10 plunger, and alines the hole 22 with the center of the fulminate charge, thereby permitting the firing pin to detonate such charge and explode the shell.

It will be noted that it is necessary for the 15 guard to be held with the block against the wall of the body, not only at the time the projectile is fired, but also during all the time the shell is in flight, since as soon as the centrifugal force is less than the strength exerted by the spring, the guard will return to 20 normal position, it being understood that the plunger will remain at the bottom of the plunger cavity as long as the projectile is in flight. Even if the guard should be pushed 25 into arming position in any way, as by a drop from a considerable height, the shell would not arm permanently, but the guard would return to normal position as soon as the plunger 30 returns to the bottom of the cavity.

30 What is claimed is:

1. In a fuse, a body, a firing pin slidable therein, a primer holder having a groove therein, a guard member slidably secured in said groove, the engagement between the 35 guard and groove being such that the guard is thereby attached to the primer holder, said primer holder and guard each having an aperture therein and means for normally holding the holder and guard with said apertures positioned out of alignment with each 40 other, said guard and primer holder being

permanently locked together when assembled.

2. In a fuse, a body, a firing pin slidable therein, a primer holder, a plate-like guard 45 member carried by and slidably secured in the primer holder, said primer holder and guard each having an aperture therein whereby said firing pin may be projected through said apertures when the latter are in registry 50 with each other, and means for normally holding said apertures out of registry.

3. In a fuse, a body, a firing pin, said pin being slidably mounted in the body, a primer holder having an opening therein permanently positioned in alignment with the firing pin, a slidably mounted guard having an opening therein, and means for normally holding the openings in the primer holder and guard out of registry, said means being 55 adapted to yield under centrifugal force and permit the opening in the guard to be moved into registry with the opening in the primer holder and into alignment with the firing pin.

4. In a fuse, a body, a firing pin slidably 60 mounted in the body, a primer holder having an aperture therein permanently positioned in alignment with the firing pin, a slidably mounted guard having an opening therein, a spring for normally holding the openings 65 out of registry with each other, said spring being adapted to yield under centrifugal force and permit the openings to be moved into registry with each other and into alignment with the firing pin, and means for preventing movement of the firing pin until the 70 openings in the primer holder and guard have been brought into absolute registry with each other.

E. R. PILLARS.
HENRY C. LEESEBERG.
